UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A DISH OR SIMILAR ARTICLE.

56,939.

Specification for Design.

Patented Jan. 18, 1921.

Application filed July 19, 1920. Serial No. 397,511. Term of patent 7 years.

To all whom it may concern:

Be it known that I, HAROLD E. NOCK, a citizen of the United States, residing at Newburyport, in the county of Essex and State of Massachusetts, have invented a new, original, and ornamental Design for a Dish or Similar Article, of which the following is a specification, reference being had to the accompanying drawing, forming a part thereof.

In the accompanying drawing Figure 1 is a plan view of a plate showing my new design applied to a section thereof, and Fig. 2 is a section on the line 2—2 of Fig. 1.

The design comprises an ornamental decoration having the configuration and

characteristics delineated embodied in a plate, the dominant feature of which is a perforated ornamentation pierced through the wall of the well of the plate within the border.

While the design is here shown applied to a plate, it is applied, with suitable adaptations, to the various dishes of a complete set, and my invention is not limited to its application to a plate.

I claim:

The ornamental design for a dish or similar article, substantially as shown and described.

HAROLD E. NOCK.
